WINDOW JACK

Filed Nov. 4, 1929

INVENTOR.
ISAAC STEINMAN,
BY
Louis Nedow

ATTORNEY

UNITED STATES PATENT OFFICE

ISAAC STEINMAN, OF PHILADELPHIA, PENNSYLVANIA

WINDOW JACK

Application filed November 4, 1929, Serial No. 404,559

My invention relates to a new and useful window jack adapted for use by glaziers, window cleaners, painters and other artisans for the purpose of affording a safe and easy access to the exterior of a window, in lieu of scaffolding and other conventional expedients heretofore known and used.

My invention further relates to a window jack of an extremely simple and durable construction and one which can be applied to, or removed from a window, from within, and without the aid of any external fastening devices.

My invention further relates to a novel window jack of a knock-down, portable construction which lends itself to easy and convenient manipulation.

To the above ends my invention consists of a horizontally disposed angle iron, an inclined leg hinged at its rear and to the rear or outer end of said angle iron, the front or inner end of said leg being connected to the front end of said angle iron by a sectional folding brace, and a hook comprising a horizontal rear section engaging the front portion of said angle iron and an inverted U-shaped portion adapted to engage a window-sill.

My invention further consists of the various other novel features of construction and advantage all as will be hereinafter described and claimed.

In the accompanying drawings:

Figure 1, represents a side elevation of a jack embodying my invention shown applied to a window.

Figure 2, represents a section on line 2—2 of Figure 1.

Figure 3, represents a fragmentary view showing details of construction.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and

organization of the instrumentalities as herein shown and described.

Referring to the drawings in which like reference characters indicate like parts, Figure 1 shows a wall 4, and a window-sill 5 to which my novel jack is applied to illustrate the manner of use. My novel jack comprises the horizontal angle iron 6 to the rear or outer end 7 of which is hinged the rear or outer end 8 of the leg 9. The front or inner ends 10 and 11 of the angle iron 6 and the leg 8 abut against the outer surface of the wall 4, and are braced by the hinged or pivoted links 12 and 13. 14 designates an inverted U-shaped hook which is adapted to engage the window-sill 5 and the outer limb 15 of which passes through a hole 16 in the top 17 of the angle iron 6 and is extended to form the horizontal arm 18 which abuts against the underside of the top 17 of said angle iron. The arm 18 is deflected upwardly to pass through the hole 19 in the top 17 of the angle iron 6 and terminates in the head or knob 20 whereby the hook 14 is permanently and rigidly secured to said angle iron. 21 designates a block which may be employed as a filler or spacer to adjust the size of the hook 14 to the width of the window-sill 5.

The operation is as follows:

Two similar jacks are used, one at each end of the window-sill 5 and a board or plank 22 is thrown across the tops 17 of the angle irons 6 of the juxtaposed jacks, said board or plank 22 forming a seat for the painter, glazier or other artisan working on the exterior of the window or its vicinity. One important advantage of my novel jack is that no extraneous fastening means are used or needed, it being merely necessary to straddle the inverted U-shaped hook 14 over the window-sill 5, with or without the use of spacers 21. This can be accomplished from within so that there is no hazard or risk of falling during the mounting of my novel jacks. When my novel jacks are not in use, the lower leg 9 is folded upwardly against the angle iron 6 with the hinged or pivoted brace sections 12 and 13 folding upon themselves inwardly in the direction of the arrow, thereby forming a compact and portable device.

While I have shown my novel invention in the form of a knock-down jack formed of angle irons 6, legs 9, and their adjuncts, it is within the scope of my invention to apply the inverted U-shaped hook 14 to an ordinary, non-collapsible wooden jack without departing from the scope of the invention or sacrificing any of its advantages.

By making the various parts out of a light rigid metal, I produce a portable jack which may be carried about at a minimum of effort.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having thus described my invention what I claim as new and desire to secure by Letters Patent is:—

1. A window jack of the character stated, comprising a horizontally extending bracket having a pair of spaced holes in the top thereof, and an inverted U-shaped hook adapted to straddle a window-sill, the inner limb of said hook engaging the inner surface of the wall below said sill and the outer limb of said hook passing downwardly through the first of said holes and being then deflected at right angles to form a horizontal arm abutting against the underside of the top of said bracket, the free end of said arm passing upwardly through the second of said holes and being formed into an enlarged head.

2. In a window jack, an inverted U-shaped hook adapted to straddle a window sill and to engage the inner surface of the wall below said sill with the inner limb thereof, a horizontally disposed angle iron, a lower inclined leg having its upper outer end hinged to the outer end of said angle iron, a sectional collapsible brace joining the inner ends of said angle iron and said brace, there being a pair of spaced holes in the top of said angle iron, the outer limb of said U-shaped hook passing downwardly through the first of said holes and being deflected at right angles to form a horizontal arm abutting against the underside of the top of said angle iron, the free end of said horizontal arm passing upwardly through the second of said holes and having an enlarged head formed thereon.

ISAAC STEINMAN.
